UNITED STATES PATENT OFFICE

2,243,985

SUCTION CLEANER

Charles H. Sparklin, Chicago, Ill., assignor to
Birtman Electric Company, Chicago, Ill., a corporation of Illinois

Application February 10, 1939, Serial No. 255,762

1 Claim. (CL 15—8)

This invention relates to improvements in suction cleaners and more especially to a cleaner of the type having a vertically movable nozzle with a rotatable brush therein.

Difficulty has been encountered with cleaners of the type mentioned when they have been left with the power turned on, standing on a carpet unattended for too long a time. In the normal operation of such cleaners the brush is in engagement with the carpet or other material being cleaned. This does not damage the carpet, however, as long as the cleaner is kept in motion or not allowed to remain in one place for too long a time. It has happened, however, that the operator has been called away from her work by a telephone call or other interruption and inadvertently left the cleaner standing in one place with the current turned on. When this has happened, the engagement of the rotating brush with the carpet in one spot for such a long time has caused undesirable wear and damage to the carpet. My improvement is designed to prevent such an occurrence.

The principal feature of my invention is the provision of means for lifting the nozzle and consequently the brush inside, out of contact with the material being cleaned, whenever the cleaner is left unattended. This raising of the nozzle is automatic and is caused by the weight of the handle when the latter is released.

Another feature of my invention is the provision of means for causing the weight of the dust bag with a predetermined amount of dirt therein to lift the nozzle, as described above, whether the handle is released or not. This makes the cleaner inoperative when the dust bag has received an accumulation of a predetermined amount of dirt and operates as a signal, showing that the bag needs emptying. I preferably provide so that either the weight of the handle or the dust bag with a predetermined amount of dirt therein will lift the nozzle.

Other features and advantages will appear more fully as I proceed with my specification.

In that form of device embodying the features of my invention, shown in the accompanying drawings: Fig. 1 is a view in side elevation; Fig. 2 is a bottom plan view; Fig. 3 is a view similar to Fig. 1 showing the nozzle in a lowered position; Fig. 4 is a view similar to Fig. 1 showing the cleaner operating on a carpet; Fig. 5 is a view similar to Fig. 4 showing the cleaner on the same carpet with the handle released and the current still turned on, the weight of the handle alone raising the nozzle from contact with the carpet;

and Fig. 6 is a similar view showing the handle in operating position but showing the weight of an accumulation of dirt in the bag raising the nozzle.

As shown in the drawings, 10 indicates a motor casing, 11 the usual fan casing, 12 the nozzle, and 13 a motor-driven brush in the nozzle. As here shown, the motor casing, fan casing, and nozzle are made in one unit. 15, 15 indicate two supporting wheels with aligned axes placed some distance back of the nozzle. The unit, including the motor casing, fan casing and nozzle, is pivotally mounted on the supporting wheels 15 by means of the stub axles 16, 16 secured to the plates 17 carried by the unit. The nozzle 12 is vertically movable with respect to the surface being cleaned. This is accomplished by pivotally supporting the unit including the motor casing, fan casing and nozzle, on the wheels 15 which lie rearwardly of the nozzle. This pivoting permits the nozzle at the forward end of the cleaner to be moved upwardly and downwardly.

The stub axles 16, 16 are so located that the nozzle is substantially counterbalanced but preferably so that it will normally tend to rock downwardly.

The two wide rollers 26, 26 form the nozzle support. These rollers are wide enough so that they will ride more or less on the surface of thick carpet and, consequently, elevate the nozzle. For example, as shown in Fig. 4, the surface being cleaned is indicated by rather thick carpet. The topmost surface of this carpet is indicated by 27. As here shown, the rollers 26 have sunk down into the carpet to some extent; that is, to the level of the line indicated by 27a; but they have not sunk down as low as the wheels 15 which are at the level of the line 27b which may be very near the bottom surface of the thick carpet.

The cleaner is shown in Fig. 3 as operating on a hard floor 28 and here the rollers 26 naturally rest at the same level as the wheels 15 and it will be seen that the nozzle consequently is also lowered.

The rollers 26 are wide enough to thus support the nozzle a slight distance above the surface of the material being cleaned regardless of its character and regardless of the degree of sink of the supporting wheels 15 into the material being cleaned.

30 indicates a rear wheel carried by the unit acting as a stop to limit the rearward pivoting of the cleaner and thus limit the upward move-

ment of the nozzle. This stop is desirable to prevent the nozzle from being raised unnecessarily high when it is elevated to move the machine from one rug to another or to avoid engagement with the fringe at the edge of a rug.

With the construction shown the rollers 26 provide additional supporting means for the nozzle or means limiting the downward movement of the nozzle operative especially when the cleaner is in operation. They are adapted to float or ride substantially on the surface of the material being cleaned. With this construction the nozzle will automatically be adjusted to the correct height, depending upon the kind, nature, softness, and thickness of the material being cleaned and yet will not be drawn down against or into the material by the suction to an objectionable extent.

It has been stated that the rollers 26 are additional supporting means for the nozzle. It is to be understood, however, that the greater part of the dead weight of the nozzle is really carried or supported by the supporting wheels 15. That is, the nozzle and the motor casing with the motor inside, and fan casing, are formed as a unit as is customary with portable suction cleaners, and the entire unit is carried by the two wheels 15, 15.

The unit, however, is pivotally mounted on the wheels as explained above so that the nozzle itself is vertically movable with respect to the surface being cleaned. The nozzle supporting means, therefore, in the form of the rollers 26, 26, act to limit downward movement of the nozzle, particularly under suction. This support for the nozzle is obtained by the rollers floating or rolling substantially on the surface of the carpet. In using the word "carpet" I mean to indicate any surface being cleaned.

The rollers 26, 26 will sink into the carpet only to a very small extent, if at all; and not nearly as much into soft carpet as the supporting wheels 15, 15. Being in the form of rollers, they will slide easily over the surface of the carpet and thus lessen the friction. The rollers preferably have considerable width, thus giving at least a line contact of considerable length and in all probability a surface contact of considerable area; thus preventing the rollers from sinking into the surface of even soft thick carpets to any great extent. By "surface" is meant the very top of the carpet. It is contemplated that the rollers will rest substantially on the upper ends of the threads forming the pile of a thick carpet without bending them over or crushing them down to any considerable extent.

It is realized, of course, that even with wide rollers the same will sink into a soft carpet to some extent, and therefore I have placed the rollers at such height that even when they thus sink into the surface to some extent, as shown in Fig. 4, the nozzle will still be held slightly above the surface. This construction may be made as desired. For example, the parts can be so made that the nozzle will just lie in contact with the surface before or after suction or even be drawn more or less tightly against the surface or into it under the force of suction. As shown in the drawings, the construction may be so that the nozzle 12 lies slightly above the surface when there is no suction. In such case suction may draw the carpet up slightly to cause contact between the nozzle and the carpet, as shown.

50 indicates the ball of the handle 50 pivoted

to the cleaner at the points 51, 51. The pivot points 51, 51 are preferably so located that forward and backward movement and acceleration imparted to the cleaner by the handle will not cause undue rocking of the cleaner on the wheels 15. That is, the resistance caused by the weight of the parts below the pivot points 51, 51, and the friction of the wheels 15, is balanced against the resistance caused by the weight of the parts above the points 51, 51, so that pressure on the pivot points 51, 51 by the handle in operating the cleaner backwardly and forwardly will not cause undue pivoting on the wheels 15, and therefore will not unduly affect the vertical movement of the nozzle 12. In speaking of the resistance offered by the weight of the parts, I refer to the inertia of the same. In order to prevent undue rocking, the pivot points 51 are preferably placed so that when the handle is in the normal operating position as indicated by the line 53, the line of force, extended below the pivot points, will lie in front of the wheels 15. It is here shown as intersecting the carpet substantially where the rollers 26 lie.

52 indicates the dust or dirt bag for the cleaner with its lower end attached to the outlet 54 of the fan casing in the usual manner. The unit is so balanced upon the wheels 15, however, that the weight of a predetermined amount of dirt in the bag 52 with the weight of the bag itself will serve to rock the unit backwardly as shown in Fig. 6 and thus elevate the nozzle and remove the brush 13 from contact with the carpet.

55 indicates a stop for the handle 50 adapted 35 to hold the same substantially in horizontal position when released, as shown in Fig. 5. There is a stop 55 on each side of the fan casing engaged by the bail 50. The handle is of sufficient length and weight so that when it is released and lies back against the stops 55 it will cause the cleaner to rock backwardly on the wheels 15 and lift the nozzle and brush 13 from engagement with the material being cleaned, as shown in Fig. 5. This will occur even if the current remains 45 turned on.

As shown in Fig. 4, in normal operation the suction may operate to raise the carpet slightly into contact with the nozzle and brush. When the carpet is thus in contact with the nozzle it will be seen that the suction will also tend to hold the nozzle in contact with the carpet, either by holding the nozzle down, or lifting the carpet, or both. In other words, the suction causes more or less of a seal between the carpet and the nozzle that must be broken before the nozzle can be raised. This seal, however, varies under different conditions. In some cases, more force is required to break it than in others. It is contemplated that the weight of the predetermined amount of dirt in the dust bag with the weight 50 of the bag, or the weight of the handle when in released position, as described above, will be sufficient to elevate the nozzle out of contact with the material being cleaned with enough force to break any seal that there might be, as just described.

It is to be particularly noted that the weight of the handle alone in released position is sufficient to elevate the nozzle. Likewise, the weight 70 of the dust bag with a predetermined amount of dirt therein alone is preferably sufficient to elevate the nozzle whether the handle is in released position or not.

It will be seen that the wheels 15 furnish the 75 main support or carriage for the cleaner proper.

That is, they take most of the weight; and therefore may be referred to as the main supporting means. The wide rollers 26, 26 may be referred to as the nozzle supporting means.

While there are shown and described certain embodiments of the invention, it is to be understood that it is capable of many modifications. Changes, therefore, in the construction and arrangement may be made without departing from the spirit and scope of the invention as disclosed in the appended claim, in which it is intended to claim all novelty inherent in the invention as broadly as permissible, in view of the prior art.

What I claim as new, and desire to secure by Letters Patent, is:

A suction cleaner of the character described, including: a casing having a downwardly opening nozzle at the forward end thereof; suction means connected to the nozzle; a rotatable cleaning member in the nozzle normally in contact with the material being cleaned; a motor in the casing for rotating the rotatable cleaning member; a handle pivotally attached to the casing and

adapted to extend upwardly and rearwardly therefrom during normal usage of the cleaner; a pair of main supporting wheels on which the casing is mounted, said wheels being only slightly to the rear of the center of gravity of the cleaner in normal usage; forward supporting means for normally maintaining the nozzle in proper operative relation to the surface being cleaned; stop means on the casing engaged by the handle upon 10 rearward and downward movement beyond that to be expected in normal usage, the weight of the otherwise unsupported handle when in engagement with the stop means being sufficient to shift the center of gravity to the rear of the main supporting wheels, whereby releasing the handle automatically causes the cleaner to pivot about the axis of said wheels to elevate the nozzle and lift the rotatable cleaning member from contact with the material being cleaned; and 15 rear supporting means normally spaced from said surface but adapted to engage it to support the cleaner in position with the nozzle elevated.

CHARLES H. SPARKLIN.
